UNITED STATES PATENT OFFICE.

CLEVELAND W. HOBART, OF BROOKSVILLE, FLORIDA.

OAR.

1,324,397.

Specification of Letters Patent.

Patented Dec. 9, 1919.

Application filed June 6, 1919. Serial No. 302,303.

To all whom it may concern:

Be it known that I, CLEVELAND W. HOBART, a citizen of the United States, residing at Brooksville, in the county of Hernando 5 and State of Florida, have invented certain new and useful Improvements in Oars, of which the following is a specification.

The object of this invention is to provide simple and efficient means whereby the 10 labor of propelling a row boat or other vessel through water will be minimized and to that end the invention seeks to provide an oar or paddle which upon its working stroke will be expanded so as to present a broad expanse of surface to the water and upon its return stroke will collapse so as to 15 cut through the water with a minimum resistance. The invention also seeks to provide simple and efficient means for limiting the expanding movement of the oar or paddle.

The invention is illustrated in the accompanying drawing, in which—

Figure 1 is a perspective view showing a 25 practical embodiment thereof;

Fig. 2 is an end view showing the blades or wings collapsed in full lines and expanded in dotted lines;

Fig. 3 is a side view of the oar showing 30 a wing or blade and the manner of mounting the same.

In the drawings, the reference numeral 1 indicates a portion of a row boat having an outstanding frame or support 2 secured to 35 and projecting from its side, which frame or support may be of any convenient or preferred construction. Upon the outer end of this frame, I mount a bracket 3 through which the oar shank or handle 4 is inserted and by which the said shank or handle is 40 supported for rocking movement. At the outer or lower end of the shank 4, I provide a stem or rod 5 upon which wings or blades 6 are supported so as to swing pivotally 45 thereabout. A pair of wings or blades is employed and each blade or wing is provided at or adjacent its ends with eyes or collars 7 encircling the stem 5 so as to swing freely about the same and after the said eyes or collars are mounted upon the stem, stop pins 8 are inserted through the stem so as 50 to prevent longitudinal movement of the wings or blades. The wings or blades are, of course, imperforate and may be of any suitable material, being preferably constructed of sheet metal so as to attain the

maximum strength with the minimum weight. Secured to the stem 5 and extending laterally therefrom between the wings or blades is an arm 9 which may be supported upon the stem in any desired manner and is illustrated as provided with an eye or collar 10 encircling the stem and equipped with a set screw 11 adapted to bind upon the stem so as to hold the arm 60 against movement. Between the free end of the arm and the free edges of the wings or blades are flexible connections 12 which will collapse, as shown in Fig. 2, when the wings are closed against the arm but will 65 freely extend upon the working stroke of the wings so that the expanding movement of the wings will be limited by the said connections becoming taut. These connections may be light chains or cables as is obvious. 70

The use of the invention is thought to be evident. The handle or shank 4 is oscillated or reciprocated so that the stem 5 with the blades thereon will work back and forth in the water. Upon the working stroke, the 80 water will enter between the free edges of the blades and by its resistance to the movement of the blades will cause the same to expand so that a large surface will be presented to the water and, consequently, a 85 strong fulcrum for the movement of the oar handle will be provided. The boat will, therefore, be propelled rapidly with a minimum expenditure of labor. Upon the return stroke of the oar handle, the force of 90 the water will be exerted against the blades at the side opposite the flexible connections so that the blades will be forced into closed position against the arm 9, as clearly shown in Fig. 2. They will then present merely 95 their edges to the water and will cut through the same with a minimum resistance and the work of the rower will be lessened.

My device is exceedingly simple in its construction and may be produced at a very low 100 cost. It will be found highly efficient in operation and is not apt to get out of order. It will always be in operative condition unless it should be accidentally damaged or become worn out through long continued use. The 105 lateral arm 9 and the flexible connections between the same and the wings do not interfere with the free movement of the blades but do positively and effectually limit both the opening and closing movements. The 110 stop arm prevents the blades coming together in the closing movement and neither

blade can swing across the line of draft. Consequently, a portion of the blade surface will always be presented to the water at the beginning of the working stroke and 5 the blades will instantly move apart.

Having thus described the invention, what is claimed as new is:

An oar comprising a shank, a pair of wings provided at their ends with collars 10 encircling the shank for pivotal movement

thereon, stops on the shank above and below said collars to prevent longitudinal movement of the wings, a stop arm rigidly secured upon the shank and extending laterally therefrom between the wings, and connections between the free end of said arm and the free edges of the wings whereby to limit the opening movement of the wings. 15

In testimony whereof I affix my signature.

CLEVELAND W. HOBART. [L. S.]
